(57) **CLAIM**

The ornamental design for a propane tank mounting assembly as shown and described.

DESCRIPTION

FIG. 1 is a top, left-side perspective view of a propane tank mounting assembly showing my new design;

FIG. 2 is a top view thereof;

FIG. 3 is a bottom view thereof;

FIG. 4 is a front view thereof;

FIG. 5 is a rear view thereof;

FIG. 6 is a left-side view thereof, the right-side view being a mirror image thereto;

FIG. 7 is a top, exploded view thereof; and

FIG. 8 is a left-side, exploded view thereof.

FIG. 9 is a top, left-side perspective view of an alternative embodiment of a propane tank mounting assembly showing my new design;

FIG. 10 is a top view thereof;

FIG. 11 is a bottom view thereof;

FIG. 12 is a front view thereof;

FIG. 13 is a rear view thereof;

FIG. 14 is a left-side view thereof, the right-side view being a mirror image thereto;

FIG. 15 is a top, exploded view thereof;

FIG. 16 is a left-side, exploded view thereof;

FIG. 17 is a top, left-side perspective view of an alternative embodiment of a propane tank mounting assembly showing my new design;

FIG. 18 is a top view thereof;

FIG. 19 is a bottom view thereof;

FIG. 20 is a front view thereof;

FIG. 21 is a rear view thereof;

FIG. 22 is a left-side view thereof, the right-side view being a mirror image thereto;

FIG. 23 is a top, exploded view thereof; and,

FIG. 24 is a left-side, exploded view thereof.
